UNITED STATES PATENT OFFICE.

STEVE HALMI, OF YONKERS, NEW YORK.

FAN ATTACHMENT FOR CARRIAGES.

Application filed April 18, 1925. Serial No. 24,101.

To all whom it may concern:

Be it known that I, STEVE HALMI, a citizen of Hungary, residing at Yonkers, in the county of Westchester and State of New York, have invented certain new and useful Improvements in Fan Attachments for Carriages, of which the following is a specification.

This invention relates to improvements in 10 fan attachments for carriages.

The primary object of the invention is to provide a fan attachment for carriages characterized by the driving of the fan blade by means of power transmission mechanism 15 adapted to be selectively connected to one of the ground engaging wheels of the carriage.

A further object of the invention is to provide novel means for permitting the connecting and disconnecting of the above referred to power transmission mechanism to the said ground engaging wheel.

Other objects and advantages of the invention will be apparent during the course of 25 the following description.

In the accompanying drawings forming a part of this specification and in which like numerals are employed to designate like parts throughout the same,

30 Figure 1 is a side elevational view of the carriage, shown in dotted lines, with the fan attachment embodying this invention properly mounted thereon,

Figure 2 is a vertical sectional view of a 35 carriage shown in Fig. 1 and illustrates the entire fan attachment in elevation,

Figure 3 is a top plan view of the fan portion of the structure shown in Figs. 1 and 2,

40 Figure 4 is a side elevational view of the structure shown in Fig. 3,

Figure 5 is a fragmentary elevational view of the device shown in Fig. 2 and clearly illustrates the mechanism employed for permitting the fan driving means to be selectively connected or disconnected with its driving means,

Figure 6 is an elevational view of the structure shown in Fig. 5, and taken at 50 right angles in respect to the showing in this figure,

Figure 7 is a vertical sectional view of the mechanism shown in Figs. 5 and 6,

55 Figure 8 is a fragmentary vertical sectional view of a friction wheel and flexible

shaft connection shown in Figs. 5 to 7 inclusive,

Figure 9 illustrates in vertical section a bevel gear connected to the opposite end of the flexible shaft shown in Fig. 8,

Figure 10 shows partly in elevation and partly in vertical section the mounting for the fan blades,

Figure 11 is a fragmentary elevational view, partly in section, of a portion of the 65 mechanism shown in section in Figs. 6 and 7, and

Figure 12 illustrates in elevation a one-way acting clutch element associated with the friction wheel shown in Figs. 5 and 8.

In the drawings, wherein for the purpose of illustration is shown a preferred embodiment of this invention, the numeral 5 designates a carriage body having mounted thereon the pivotally movable top 6 which is intended to have suitably fastened to the inner face of the upper portion of the same the spider 7. This spider acts as the mounting for the fan blades which includes a spindle 8 threaded at its upper end 9, see Fig. 10, 75 for being received within the aperture 10 formed in the hub portion of the spider 7. This spindle 8 is shown in Fig. 10 as having a reduced trunnion 11 upon which is mounted the hub 12 which carries the fan 80 blades 13. This hub 12 is provided with ball bearing races 14 within which the ball bearings 15 are located. The extreme end of the spindle 8 is reduced and externally 85 screw threaded at 16 for receiving the binding nut 17 which holds the fan blades and their hub in place. The hub 12 has formed integrally therewith a bevel gear 18, the purpose of which will be disclosed at a later point. The spider 7 has suitably fastened 90 thereto the protector frame 19, clearly illustrated in Figs. 1 to 4 inclusive. The spider 7 has suitably connected to or formed integrally with one of its arms a bearing bracket 20 having mounted therewithin the bearing bushing 21 which is held against rotation by the set screw 22, see Fig. 9. This bearing bushing 21 has journaled therein the stub shaft 23 which has rigidly mounted 95 upon one projecting end a bevel gear 24 shown in Figs. 2 and 4 as meshing with the bevel gear portion 18 carried by the fan hub 12.

The stub shaft 23 has an annular flange 110 formed adjacent its opposite end which

prevents the withdrawal of the said shaft from the bearing bushing 21 toward the side where the bevel gear 24 is located. This flanged end of the stub shaft 23 is provided with a bore 26 into which projects a flexible shaft 27 which is suitably fastened in said bore. This flexible shaft 27 is surrounded by a suitable flexible casing 28 which extends with the shaft in the manner illustrated in Figs. 1 and 2 to terminate at their lower ends in close proximity to the ground engaging wheel 29 of the carriage body 5. The flexible casing and shaft 28 and 27 respectively are suitably supported at desired intervals by the mounting straps 30 which are fastened to the carriage body 5.

The opposite ends of the shaft and casing 27 and 28 respectively are shown in Fig. 8. The shaft end is received in the bore 31 formed in one end of the stub shaft 32 which is journaled in the bearing bushing 33 clamped between the adjustable parts 34 of a two-part mounting which will be described in detail at a later point. This stub shaft 32 is provided with a flange 35 for preventing outward movement of the stub shaft away from the flexible shaft 27. The opposite projecting end of the stub shaft 32 has fastened thereto the element 36 of a one-way acting clutch structure which cooperates with the opposed clutch structure 37 formed integrally with the hub 38 of the friction wheel 39 having mounted on its periphery the rubber tire 40. This wheel 39 is longitudinally movable and is normally held in position for causing its clutch structure 37 to operatively cooperate with the clutch structure 36 for providing a connection between the wheel 39 and the stub shaft 32. The spring 41 is intended to maintain these clutch structures 36 and 37 in operative relation and is held in place by the washer 42 which is retained upon the end of the stub shaft by the nut 43.

The mounting members 34 for the bearing bushing 33 are carried by the plunger 44 which extends into the cylinder 45 through the packing nut 46. The lower end of this plunger 44 has threaded thereon the nut 47 which is employed for retaining in place the spring 48 which bears at its upper end against the inner end of the packing 46 and at its lower end against the nut 47 for functioning to move the plunger 44 downwardly through the cylinder 45. This cylinder 45 has a slot 50 formed in one side through which projects the operating handle 51 of a cam 52 which is pivoted on the pin 53. This cam 52 functions to force upwardly upon the plunger 44 for compressing the spring 48. The lower end of the cylinder 45 is formed substantially solid, as at 54, and is provided with a threaded bore 55 which adjustably receives the threaded stem 56 carried by the jaw 57 which has adjust-

able thereon a second clamping jaw 58. The threaded member 56 is held in any desired adjusted position by the lock nut 59.

It will be seen, by inspecting Figs. 2 and 5 to 7 inclusive that the jaws 57 and 58 are employed for clamping therebetween the supporting axle 60 for the ground engaging wheel 29 and are intended to support the cylinder 45 and its associated elements in such a manner that the friction wheel 39 will overlie the tread of the ground engaging wheel 29.

The operation of this device may be described as follows:

It will be seen by inspecting Figs. 2, 5 and 6 that the treads of the wheels 29 and 39 are in frictional engagement. With these wheels so arranged, movement of the carriage in a forward direction will cause the friction wheel 39 to rotate and the clutch elements 36 and 37 will cooperate for connecting the hub 38 of the wheel 39 to the stub shaft 32. Rotation of the stub shaft 32 will cause the flexible shaft 27 to rotate for causing similar rotation of the stub shaft 23 connected to its opposite end and the bevel gear 24 carried by this stub shaft. Due to the meshing of the bevel gear 24 with the bevel gear portion 18 of the fan blade hub 12, this movement of the carriage in a forward direction will cause the fan blades 13 to rotate for creating a breeze or draft within the carriage top and body 6 and 5 respectively.

If the carriage is moved rearwardly the friction wheel 39 will be rotated in the opposite direction for causing the clutch elements 37 and 38 to become disengaged by the movement of the wheel hub 38 longitudinally of the stub shaft 32 against the tension of the spring 41.

When the operator of the carriage does not desire to have the fan in operation, downward movement upon the operating handle 51 of the cam 52 will cause the plunger 44 to be moved longitudinally outwardly of the cylinder 45 for elevating the tread of the friction wheel 39 off of the tread of the ground engaging wheel 29. The carriage may then be moved in either direction without causing rotation of the friction wheel 39.

It is to be understood that the form of this invention herewith shown and described is to be taken as the preferred example of the same, and that various changes in the shape, size, and arrangement of parts may be resorted to without departing from the spirit of the invention or the scope of the subjoined claims.

Having thus described the invention, I claim:

1. In a device of the type described, the combination with a wheeled carriage, of a fan mounted thereon including a series of

blades carried by a hub, and a gear formed integrally with the hub; a flexible shaft, a gear connected to one end of the flexible shaft and meshing with the gear part of the 5 fan hub, a friction wheel connected to the other end of the flexible shaft, a support for the friction wheel including a tubular member vertically supported on an axle of the carriage, a downwardly tensioned rod 10 slidable in the tubular member and supporting the friction wheel at its upper end, and means for selectively moving the tread of the traction wheel into and out of engagement with the tread of one of the 15 ground-engaging wheels of the carriage.

2. In a device of the type described, the combination with a wheeled carriage, of a fan mounted thereon including a series of blades carried by a hub, and a gear formed 20 integrally with the hub; a flexible shaft, a gear connected to one end of the flexible shaft and meshing with the gear part of the fan hub, a friction wheel connected to the other end of the flexible shaft, a support for 25 the friction wheel including a tubular member vertically supported on an axle of the carriage, a downwardly tensioned rod slidable in the tubular member and supporting the friction wheel at its upper end, and a 30 cam lever pivoted in the side of the tubular

member engaging the lower end of the tensioned rod for selectively moving and holding the tread of the friction wheel into and out of engagement with the tread of one of the ground engaging wheels carried by said 35 axle.

3. In a device of the type described, the combination with a wheeled carriage, of a fan mounted thereon including a series of blades carried by a hub, and a gear formed 40 integrally with the hub; a flexible shaft, a gear connected to one end of the flexible shaft and meshing with the gear part of the fan hub, a friction wheel connected to the other end of the flexible shaft, and means 45 adjustably carried by an axle of the carriage for selectively moving and holding the tread of the friction wheel into and out of engagement with the tread of one of the ground engaging wheels carried by said 50 axle, said last mentioned means including a telescopic support, resilient means for drawing the inner telescoping member inwardly of the outer member, and means for manually moving the inner telescoping member 55 outwardly of the outer member.

In testimony whereof I affix my signature.

STEVE HALMI.
